UNITED STATES PATENT OFFICE.

HERBERT B. COLLINS, OF CHICAGO, ILLINOIS, ASSIGNOR TO SWIFT AND COMPANY, OF CHICAGO, ILLINOIS, A CORPORATION OF ILLINOIS.

FILLER FOR EGG-CASES.

No. 926,049.

Specification of Letters Patent.

Patented June 22, 1909.

Application filed December 23, 1907. Serial No. 407,670.

To all whom it may concern:

Be it known that I, HERBERT B. COLLINS, a citizen of the United States, residing at Chicago, in the county of Cook and State of Illinois, have invented certain new and useful Improvements in Fillers for Egg-Cases, of which the following is a specification, reference being had to the accompanying drawings.

10 My invention relates to packing cases for eggs and similar fragile articles, and particularly to a new and improved filler for such cases, and the object of the invention is to provide a new and improved filler which 15 is designed more perfectly to protect the eggs and keep them from breaking, and particularly to provide a new and improved bearing strip for such fillers, which bearing upon the end of the box in which the eggs 20 are inclosed for shipment will tend to prevent the breaking of the eggs.

As is well known, eggs are packed for shipment in shipping boxes containing a number of fillers which are constructed of 25 strips of cardboard or similar material so as to form individual cells for the eggs. A number of these are placed one above the other in the shipping cases with interposed "flats" of cardboard, or similar material, 30 between the layers. The boxes are usually constructed with a central partition having a space upon each side of the central partition of sufficient size to contain a series of fillers, one above the other, each containing 35 thirty-six or three dozen compartments. The central partition being put in after the box is completed it frequently happens that it is not located exactly centrally, and hence, while the fillers fit the box from side to side 40 and the eggs are protected by the projecting ends of the cardboard strips from breakage, the compartments between the central partition and the end of the box vary somewhat, so that the projecting ends are apt to be 45 come bent over on the side where the compartment is too short and do not quite reach the partition on the side in which the compartment is a little too long, causing the eggs to become broken, particularly at the 50 ends.

It is the object of my invention to provide a filler which will obviate these objections, and to this end it consists in providing the fillers with what may be called

"bearing strips", located preferably at the 55 ends of the fillers which come against the ends of the box and the central partition, and which consist of a corrugated strip having pairs of deeper corrugations with intermediate shallower corrugations, the bearing 60 strips being secured to the ends of the strips which constitute the filler at the convex side of the deeper corrugations. The filler having this peculiar form of corrugated bearing strip thus affords sufficient elasticity at 65 its ends to provide against the breaking of the eggs and also by reason of the shallower intermediate corrugations forms spaces somewhat larger than the spaces in the other compartments within which eggs slightly 70 larger than the average size may be placed.

In the drawings,--Figure 1 is an isometric view of a case containing my improved fillers with a portion of the case removed to show the construction more clearly; Fig. 2 is an 75 enlarged detail, being a top or plan view of a portion of the corrugated bearing strip to show more clearly the form of corrugations.

Referring to the drawings,--3 indicates a 80 case divided by a central partition 4. 5 indicates the fillers, which are composed of strips of cardboard 6-7 which are interlocked in the usual and well-known way, so that they may be folded together flat for 85 shipment. The strips 6-7 project at their ends, forming bearing projections 8 which are adapted to bear against the side of the box to keep the strips which lie adjacent thereto away from the sides of the box to 90 form an elastic bearing for the fillers against the box to prevent breakage.

9 indicates flats, which are placed between the different layers of fillers.

10 inlike bearing strips, which are located preferably only at the ends of the fillers, as shown, so as to bear against the ends of the case and the intermediate partition 4. As is best shown in Fig. 2, the bearing strips are provided with cross or vertical corrugations consisting of deep corrugations 11 and shallower corrugations 12 intermediate the deep corrugations 11. The bearing strips 10 are secured to the filler by passing the ends of the strips 7 through the end pieces at the 105 deeper corrugations 11 entering them from the convex side. As is best shown in Fig. 2, this arrangement is such that the shal-

lower corrugations 12 are removed slightly from the end of the box or from the central partition 4, bearing upon the box at the ends of the deeper corrugations. The result of this arrangement is that an allowance is made for differences in length between the two partitions of the box caused by the frequent slight misplacing of the central partition and the eggs in the end rows are protected from breakage when the box is shipped. The shallower intermediate corrugations also, it will be observed, form a somewhat deeper row of cells at the end of the filler into which the slightly oversized eggs may be placed.

I have described my construction as having my improved bearing strips only at the ends of the fillers which bear against the ends of the box and the central partition, and this will usually be sufficient as the boxes are usually accurately enough built as to width to allow the projecting ends 8 to afford sufficient elasticity to prevent breakage in the outside rows of eggs toward the side of the box, but, of course, my improved bearing strip may be located upon all four sides of the filler, if desirable.

That which I claim as my invention, and desire to secure by Letters Patent, is,—

30 1. A filler for cases comprised of a plurality of intersecting strips having corrugated bearing pieces secured at the outside ends of said strips, each of said corrugated bearing pieces having pairs of deeper corruga-

tions and intermediate shallower corruga- 31 tions.

2. A filler for egg cases, consisting of a plurality of intersecting strips and corrugated bearing pieces having pairs of deeper corrugations and intermediate shallower corrugations and secured to the ends of said intersecting strips at the convex portion of 40 said deeper corrugations.

3. A corrugated bearing strip for egg fillers having pairs of deeper transverse corrugations and intermediate shallower corrugations. 45

4. A filler for egg cases, composed of a plurality of intersecting strips having corrugated bearing pieces secured at the outside end of said strips, each of said corrugated bearing pieces having between the pairs of strips which intersect it pairs of deeper corrugations and intermediate shallower corrugations. 50

5. A filler for egg cases, consisting of a plurality of intersecting strips and corrugated bearing pieces, said corrugated bearing pieces having between the pairs of strips which intersect it pairs of deeper corrugations and intermediate shallower corrugations and secured to the end of said intersecting strips at the convex portion of 55 said deeper corrugations. 60
